Primary Examiner — Adir Aronovich*Assistant Examiner* — Etiene Salgado-Rodriguez(74) *Attorney, Agent, or Firm* — Sheridan Ross P.C.(57) **CLAIM**

The ornamental design for a protective sleeve, as shown and described.

DESCRIPTION

FIG. 1 is a front perspective view of a protective sleeve showing my new design;

FIG. 2 is a top plan view thereof;

FIG. 3 is a front elevation view thereof;

FIG. 4 is a right elevation view thereof;

FIG. 5 is a left elevation view thereof;

FIG. 6 is a rear elevation view thereof; and,

FIG. 7 is a bottom plan view thereof.

The broken lines showing a zipper illustrate environment and form no part of the claimed design.
